UNITED STATES PATENT OFFICE.

JOHN T. WHEATMAN, OF SEATTLE, WASHINGTON.

GRINDING-MACHINE.

No. 843,725.

Specification of Letters Patent.

Patented Feb. 12, 1907.

Application filed January 17, 1906. Serial No. 206,601.

To all whom it may concern:

Be it known that I, JOHN T. WHEATMAN, a citizen of the United States, residing at Seattle, in the county of King and State of Washington, have invented certain new and useful Improvements in Grinding-Machines, of which the following is a specification, reference being had therein to the accompanying drawings, in which—

10 Figure 1 is a front elevation, Fig. 2 a side elevation, and Fig. 3 a plan view, of an embodiment of my invention. Fig. 4 is a perspective view of a planer-knife, provided along its cutting edge with a rabbet and illustrating a class of work for which the invention is especially adapted.

This invention relates to grinding-machines, and has for its object the forming of grooves or rabbets in the edges of bars and 20 more particularly in planing-knives.

The invention consists in the novel construction, adaptation, and combination of devices as will be hereinafter described in connection with the said drawings.

25 The frame of the machine comprises a bed-plate 5, a standard 6, which supports in suitable journal-boxes an arbor 7, carrying a pulley 8 for a driving-belt, and two flange-collars 9, whereby an emery-wheel 10 is detachably mounted upon the arbor.

Slideably secured to the frame-standard is a work-bed 11, which is adjustably raised or lowered by means of a screw 12, passing through an internally-screw-threaded boss 13, 35 formed or provided upon the said bed. The bed is retained at the requisite vertical position by means of jam-nuts upon the said screw or desirably by a clamping-bolt, such as 14, passing through apertured ears 15 of the bed. At or near the front edge of the bed is a transversely-arranged rib 16, having oppositely-inclined front and back edges 16', which fits into a correspondingly-shaped recess 17 of a work-table 18 and forms a guide 40 therefor. A reciprocating traverse motion is communicated to this table by suitable means, such as a rack 19, provided thereon, being engaged by a pinion 20, mounted upon a spindle 21, which is journaled in boxes 45 22, carried by said bed, and rotated by a crank 23.

Attached to the upper face of the bed is a face-plate 24, provided with rectangular flanges 25, having slots 26, through which pass the retaining-bolts 27, which engage in threaded holes therefor in the top face of said carriage and is adjustably moved by set-screws 28, which extend through lugs 29 of the carriage and having their ends bear against said face-plate or upon the work secured thereto. The face-plate is likewise provided with horizontal slots 30 for the bolts 31 with which the work is secured in place and where planer-knives, such as P, are being operated upon also pass through the slots 32 of the latter.

The knives or other work being secured to the face-plate and adjusted in a horizontal and vertical direction by moving the latter and the bed, as before explained, the carriage is then moved by manipulating the crank 23 backward and forward beneath the driven emery-wheel to effect the desired cut upon the knives and grind out the rabbets 34 thereof. Where the wheel is of the proper thickness, two knives can be oppositely secured to the face-plate and ground simultaneously.

The advantages of the invention reside in the facility with which knives or the like may be adjustably set and accurately ground, in the simplicity of the mechanism, and in the relatively low cost of construction.

Having described my invention, what I claim as new, and desire to secure by Letters Patent, is—

In combination with a bed of a grinding-machine, a work-table, a face-plate composed of rectangular side flanges, and a vertically-extending part, said flanges being clamped to said table, upwardly-projecting lugs carried by the table, set-screws extending through said lugs and bearing against said central part of the face-plate on opposite sides thereof, said central part being slotted to receive means to clamp the work thereto.

In testimony whereof I affix my signature in presence of two witnesses.

JOHN T. WHEATMAN.
